Primary Examiner — Michelle E. Wilson*Assistant Examiner* — Sanjeev Paul(74) *Attorney, Agent, or Firm* — Buckert Patent & Trademark Law Firm PC; John F. Buckert(57) **CLAIM**

The ornamental design for a pelvis support assembly, as shown and described.

DESCRIPTION

FIG. 1 is an isometric view of another pelvis support assembly showing my new design.

FIG. 2 is a side view of the pelvis support assembly of FIG. 1.

FIG. 3 is a top view of the pelvis support assembly of FIG. 1.

FIG. 4 is a front view of the pelvis support assembly of FIG. 1; and,

FIG. 5 is a bottom view of the pelvis support assembly of FIG. 1.

1 Claim, 2 Drawing Sheets(56)
